ATTORNEY

UNITED STATES PATENT OFFICE.

ANTON HOVORKA, OF CHICAGO, ILLINOIS.

HINGE.

1,089,707.

Specification of Letters Patent. Patented Mar. 10, 1914.

Application filed June 16, 1913. Serial No. 773,973.

To all whom it may concern:

Be it known that I, ANTON HOVORKA, a citizen of the United States, residing at Chicago, in the county of Cook and State of Illinois, have invented certain new and useful Improvements in Hinges, of which the following is a specification.

The hinge which is the subject matter of the present application for patent is designed more particularly for crates, boxes and the like.

It is the object of the invention to provide a strong and durable hinge, the same being made entirely of wire, so that it may be easily and cheaply manufactured, and to this end the invention consists in a novel combination and arrangement of parts to be hereinafter described and claimed, reference being had to the accompanying drawing forming a part of this specification.

In the drawing Figures 1 and 2 are perspective views showing the two hinge parts separated. Fig. 3 is a cross section showing the hinge applied to a box or crate.

Referring specifically to the drawing one member of the hinge consists of a piece of wire which is bent intermediate its ends to form two parallel shanks 5 which are spread at the bend to form an eye 6. Adjacent to the eye the shanks have a lateral bend 7 from which the eye extends laterally, so that it is offset to one side of the shanks. The other ends of the shanks have lateral bends 8. The other hinge member is composed of a wire shank 9 bent at one end into the form of a hook 10 to engage the eye 6, and having at the other end a lateral bend 11.

Fig. 3 shows two hinge members assembled in place on a box or crate, the rear wall

of which is indicated at 12 and the lid at 13. 40 A fragment only of these parts is shown. To the outer face of the wall 12, at the top thereof, is secured a strip 14 between which strip and the wall the shanks 5 are placed and held. The bends 8 engage the bottom 45 edge of the strip, and the bent portion 7 engages the top of said strip, which latter edge is flush with the top edge of the wall 12, and the eye 6 stands up from said edge of the strip. To the top of the lid 13 is secured 50 a strip 15 which comes flush with the rear edge of the lid, and between these parts the shank 8 of the other hinge member is held, the hook 10 projecting a sufficient distance so that it may extend through the eye 6. 55 The bend 11 engages the front edge of the strip.

The hinge herein described is simple, strong and durable, and can be readily applied. In addition to its use in connection with a lid, it may be used for connecting the walls of folding crates and boxes.

I claim:

A hinge comprising a wire member bent intermediate its ends and brought together 65 to form parallel shanks, the wire at the bend being spread to form an eye, and the shanks having lateral bends at one end to offset the eye therefrom and to form a shoulder, said eye extending laterally from the shoulder, 70 and a second wire member having a hook which engages the eye.

In testimony whereof I affix my signature in presence of two witnesses.

ANTON HOVORKA.
